CLAIM

The ornamental design for a display screen portion with graphical user interface, as shown and described.

DESCRIPTION

The patent or application file contains at least one drawing executed in color. Copies of this patent or patent application publication with color drawing(s) will be provided by the Office upon request and payment of the necessary fee.

The sole FIGURE is a front view of a display screen or a portion thereof with graphical user interface showing our new design

The outermost dot-dash broken line perimeter in the FIGURE illustrates a display screen or portion thereof and forms no part of the claimed design. The remaining broken lines, including all text features, illustrate portions of a graphical user interface and form no part of the claimed design.
